CIGAR FILLER PRESS

Herbert Rudolf Kasper, Dresden, Germany, assignor to "Universelle" Cigarettenmaschinenfabrik J. C. Mueller & Co., Dresden, Germany

Application December 16, 1937, Serial No. 180,063
In Germany December 24, 1936

4 Claims. (Cl. 131—87)

This invention relates to the manufacture of cigar fillers, and more particularly to an improved press adapted for use in the compression of the filler.

An object of this invention is to provide an improved press of the endless type which is so constructed that the movement of the conveyor accomplishes the necessary operation of closing, holding and finally opening the press members.

Another object of this invention is to provide spring-pressed closure means for the press members, and to use in combination therewith a positive opening means for press members so that the press members will at the proper station or zone in the movement of the conveyor be swung to an open or filler receiving position.

The filler compressing devices at present available have been found unsatisfactory so far as the even compression of the filler is concerned, the filler being of an uneven density due to the pivotal movement of the upper mold or press member and to the manner of holding the upper press member. This invention has, therefore, a still further object in the provision of a pivoted upper mold or press member and means active after the upper mold or press member has been moved to an operative position for holding the upper mold in a clamping or pressing position until the unloading station has been reached, the length of the conveyor and the speed of the movement of the conveyor determining the length of time that the press members are held in clamping or pressing position.

A further object of this invention is to provide a plurality of filler compressing members which are secured to an endless chain or carrier and to dispose means in the path of the movement of such members to effect the closing, compression, holding and finally the opening of such members during the continuous movement of the members on the carrier.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is detail side elevation of a plurality of cigar filler compressing devices constructed according to an embodiment of this invention mounted on a conveyor or carrier which is shown in fragmentary form.

Figure 2 is a top plan of the devices shown in Fig. 1.

Figure 3 is a detail front elevation of a lower mold and holder therefor removed from the conveyor or carrier.

Figure 4 is a sectional view taken on the line IV—IV of Fig. 3.

Figure 5 is a transverse sectional view taken substantially through the center of the upper mold or press member.

Figure 6 is a fragmentary sectional view taken on the line VI—VI of Fig. 2.

Referring to the drawings, the numeral 1 designates a conveyor or carrier in the form of a chain which is trained over sprockets 2 connected to a suitable source of power (not shown). A lower mold or press member 3 is secured or held in a holder 8 which is secured as by bolts 9 to the chain or carrier 1. The mold 3 is provided with a pocket 4 therein forming one-half of the mold for the cigar filler, and preferably the mold 3 is removably secured in the holder 8 by means of ribs 10 carried by the holder 8 which engage in grooves 10a provided in the opposite sides of the mold 3. In practice there are also preferably two chains or carriers 1, and the holder 8 is provided with pairs of dependent lugs 9a adjacent each end thereof through which the bolts 9 engage. The mold 3 is held against longitudinal movement in the holder 8 by means of a pin 21 carried by a spring 19 which is secured as by bolts 20 to a side of the holder 8.

An upwardly curved arm 11 is secured to a side of the holder 8, and a curved lever or arm 13 is pivoted as at 12 to the stationary arm 11. The lever 13 is provided at the free end thereof with an eye or boss 14 in which a shaft 15 is slidably disposed. The shaft 15 has secured to the lower end thereof an upper mold holding or supporting member 16, and a base member 5 is removably mounted on the holder 16. The holder 16 is provided with opposed ribs 18 which engage in complementary grooves 18a in the base member 5, and a pin 24 carried by a spring 23 engages in a suitable hole in the base member 5 so as to hold the base member 5 against longitudinal movement in the holder 16. The spring 23 is secured as by a bolt or screw 22 to a lug 17 formed on the holder 16.

The upper mold holding member 16 has an upper mold 6 secured to the under side thereof, and this mold 6 is provided with a pocket 7 complementary to the pocket 4 in the lower mold 3. The upper mold 6 with the supporting means 16 therefor is held against turning rela-

tive to the lever or arm 13 by means of dependent guide member 27 fixed to the arm 13 and engaging against one side of the holding means 16. A spring 25 is disposed about the upper end of the shaft 15, the lower end of the spring 25 engaging against the upper side of the lever 13, and the upper end of the spring 25 engaging against a head 26 carried by the upper end of the shaft 15. The spring 25 constantly urges the mold supporting means 16 to an upper released position.

The lever 13 is biased to a released position by means of a spring 29 which at one end engages a pin 28 fixed to the stationary arm 11 and at the other end engages a pin 30 fixed to the lever or rock arm 13. A stop member 32 is fixed to the stationary arm 11 and is adapted to limit the upward swinging of the lever or rock arm 13 to a released or open position.

An upper mold closing member comprising a horizontal bar 42 and an upturned end 41 is supported by means of supporting bars 43 from the frame of the machine in the path of the movement of the molds or pressing members. As shown in Fig. 1, the forward end portion 41 of the mold closing means is upwardly curved sufficiently so that the opened mold and supporting means therefor will engage against the end 41 and will then be swung downwardly and held in a lowermost position by the straight portion 42 which is disposed above and parallel with the upper run of the conveyor or carrier 1. At a suitable point in the movement of the pressing members along the length of the holding member 42, the upper holding means 16 is forced downwardly against the tension of the spring 25 by means of a rock lever or pressure means 44. The rock lever 44 is pivotally supported on a pivot 45 engaging a bearing 46 movably mounted in the frame of the machine, and the outer end 53 of this lever 44 is adapted to be engaged with a suitable lever operating means (not shown), which may be either manual or mechanical and forms no part of the present invention.

The lever 44 is provided at its inner end with a boss 47 in which a plunger 50 is slideable, the plunger 50 being urged downwardly by means of a spring 49. A stem 48 is also slideable in the boss 47 and engages the plunger 50. The upper end of the stem 48 is provided with a ring 51 which limits the movement of the stem 48 and the plunger 50 in the boss 47. Preferably the stem 48 is fixed to the plunger so that these parts will move as a unit. The plunger 50 is disposed in the path of the head 26 of the shaft 15, so that when the rock lever 44 is rocked downwardly the shaft 15 will be moved downwardly.

A pair of holding members 35 are swingably mounted on pivotal members 34 rotatably mounted in bosses 33 disposed on opposite sides of the arm 11 and fixed to the lower holder 8. The inner ends of the holding members 35 are provided with outstanding pins 36, and a spring 37 connects opposite pins 36 and constantly urges the holding members 35 to a released position. When the holding members 35 are in released position they are disposed in substantial alignment.

After the mold 6 has been forced downwardly into the mold 3 by means of the lever 44, the mold holding members 35 are swung into operative position over the top of the upper holding member 16 by means of opposed rollers 55 which are carried by bracket members 54 secured to the sides of the frame. The bearing 46 is preferably

supported on the upper end of a rock lever 46a, which is adapted to move forwardly in the depressed position of the lever 44 so as to maintain the shaft 15 in compressed position until the holding members 35 are swung to holding or clamping position by means of the rollers 55. The rock lever 46a may be operated by either mechanical or manual means which however form no part of the present invention. The upper side of each holder 16 is provided with a rounded upstanding rib 40 which is engaged by the clamping members 35. An outstanding pin 41a is secured to one side of the lever 13 and is disposed in the path of the upwardly curved end portion 41 of the holding member 41, 42 so as to swing the upper mold 6 with the supporting means therefor downwardly to a pressing or substantially closed position.

When the clamping or holding members 35 are swung to operative position, the mold passes out from under the holding member 42 and continues around the conveyor to the discharging position. This discharging position of the mold is in the present instance disposed closely adjacent the loading station, the latter station being designated as *v* in Fig. 1. The discharging position or station is designated *u* in Fig. 1, and in this position the mold is moving vertically around the adjacent end of the conveyor or carrier 1. The frame of the machine is provided at the discharge end thereof with a U-shaped bracket or supporting member 57 which encloses the end of the carrier 1 and through which the various molds are adapted to pass.

The bracket 57 is provided on the bight or outer end thereof with a pair of spaced apart angularly disposed releasing members 56 secured to the bracket 57 by means of bolts 58. The releasing members 56 are disposed in downwardly convergent relation, as shown in Fig. 6, with the lower end of each member 56 adapted to engage inside of a pin or extension 62 carried by each holding member 35. As each mold moves vertically past the releasing members 56 the holding members 35 are moved outwardly until they ride off of the ribs 40, at which time the spring 37 will swing the holding members 35 outwardly to completely released position.

In order to provide a means whereby the upper mold 6 may be positively moved to a released position, there is provided a releasing member 63 which is supported by means of an arm 64 secured to the bracket 57. The releasing member 63 is disposed in the path of the head 26 and is inclined to the vertical so that as the head 26 moves upwardly the head 26 will slide along the surface of the releasing member 63 and will thus be positively forced outwardly. The engagement of the head 26 with the releasing member 63 will not be effected at all times, as the spring 25 will normally move the mold 6 to an open or released position. However, in the event the mold 6 should stick in the pocket or recess 4 of the lower mold 3, and the tension of the spring 25 is not sufficient to withdraw the mold 6 from the pocket 4, the head 26 will ride over the releasing member 63 and thus forcibly withdraw the mold 6 from the pocket 4.

A guide member 60 carried by an arm 59 secured to the bracket 57 is adapted to engage a lateral extension 61 carried by the lever or arm 13 so that during the movement of the mold through the bracket 57 the lever 13 will be held against rocking under the tension of the spring 29. As soon as the lever 13 passes the upper end

of the guide member 60 the lever 13 will be swung to a released position by the spring 29.

In the operation of this cigar filler compressing means, the carrier or conveyor 1 has the upper run thereof moving to the left as viewed in Fig. 1. At the receiving station *v*, the mold is open and the desired uncompressed filler is placed in the pocket 4 of the lower mold 3. The placement of the material in the pocket 4 may be done manually or by any suitable delivery means. As the carrier 1 moves to the left, the outstanding pin 41a strikes the forward end 41 of the stationary holding means, thus swinging the lever or arm 13 downwardly. When the mold arrives at the compressing station *x*, the rock lever 44 is rocked downwardly so as to compress the spring 25 and move the upper mold 6 into the pocket 4 of the lower mold 3. The compressed position of the upper mold 6 is maintained by the swinging of the lever supporting member 46a until the forward movement of the carrier 1 brings the outstanding and substantially aligned holding members 35 into engagement with the rollers 55. At this point the rock lever 44 is raised and the compressed mold passes along the carrier, returning on the lower run of the carrier to the releasing station *u*, at which point the releasing members 56 engage the lugs or extensions 62 and swing the holding members 35 to released position. The lever holding guide 60 at this point engages the lever 13, and in the event the mold 6 should stick in the pocket 4 the head 26 will engage the releasing member 63 and be moved thereby into released position. As soon as the lever or arm 13 passes the upper end of the holding guide 60, the spring 29 will swing the lever or arm 13 upwardly to released position determined by the stop member 32. The compressed filler in the lower pocket 4 may then be removed from the pocket by manual or other means and an uncompressed filler inserted in the pocket 4.

It will be apparent from the foregoing that the length of the carrier 1 will determine the length of time that the filler is held within the mold pockets 4 and 7, this compressing period being also dependent upon the speed of the carrier 1.

It is of course understood that various changes and modifications may be made in the details of construction of this invention, such changes and modifications being restricted only by the scope of the appended claims.

What is claimed is:

1. A cigar filler compressing means comprising an endless conveyor, a lower mold member, means securing said member to said conveyor, an upper mold member, means swingably securing said upper mold member on said lower mold member, means normally

biasing said upper mold member to open position, stationary means engageable with said upper mold member for swinging said upper mold member to a partially closed position, a mold closing lever engageable with said upper mold and movable therewith for a short distance to hold the upper mold in closed position, a pair of spring-operated clamping arms for each mold, and stationary means engageable with said arms when said lever is in mold closing position to swing said arms to clamping position.

2. A cigar filler compressing means comprising a conveyor, a lower mold member secured to said conveyor, a rock arm carried by said mold member, a spring-pressed upper mold member carried by said rock arm, means normally biasing said rock arm to released position, means engageable with said rock arm for swinging said rock arm to operative position, pressure means for moving said upper mold member to compressed position, and means active after said upper mold member has been moved to compressed position for holding said upper mold in compressed position, said latter means including a pair of clamping arms pivotally carried by said lower mold and biased to a released position, and stationary means engageable with said arms to swing said arms to clamping position.

3. A cigar filler compressing means comprising a conveyor, a lower mold member secured to said conveyor, an upper mold member movably supported relative to said lower mold member, stationary means engageable with said upper mold member for moving said upper mold member in the direction of said lower mold member, holding means for holding said upper mold member in operative position, said holding means including a pair of clamping arms pivotally carried by said lower mold and biased to a released position, stationary means engageable with said arms to swing said arms to clamping position, and releasing means engageable with said holding means for releasing said upper mold member.

4. A cigar filler compressing means comprising a conveyor, a mold member secured to said conveyor, a second mold member, means swingably securing said second mold member on said first mold member, yieldable means constantly urging said second mold member to released position, stationary means engageable with said second mold member for swinging said second mold member into a lowered position, spring-operated holding means swingably carried by said first mold member for holding said second mold member in engaging position, and stationary means engageable with said holding means after said second mold member has been swung into lowered position for swinging said holding means to engaging position.

HERBERT RUDOLF KASPER.
